UNITED STATES PATENT OFFICE

108,539

DESIGN FOR A COMBINED ASHTRAY AND CIGARETTE PACKAGE OPENER

Herbert Flohr, Cincinnati, Ohio, assignor of one-third to Otto Creutz and one-third to William G. Courtney, both of Cincinnati, Ohio

Application May 25, 1937, Serial No. 69,536

Term of patent 7 years

To all whom it may concern:

Be it known that I, Herbert Flohr, a citizen of the United States of America and a resident of Cincinnati, in the county of Hamilton and State of Ohio, have invented a new, original, and ornamental Design for a Combined Ash Tray and Cigarette Package Opener, of which the following is a specification, reference being made to the accompanying drawing, forming a part thereof.

Fig. 1 is a top plan view of a combined ash tray and cigarette package opener showing my new design.

Fig. 2 is a side elevation thereof.

Fig. 3 is a perspective view thereof.

I claim:

The ornamental design for a combined ash tray and cigarette package opener as shown.

HERBERT FLOHR.
